(57) CLAIM

The ornamental design for a water recreation craft, as shown and described.

DESCRIPTION

FIG. 1 is a left rear perspective view of our design; FIG. 2 is a left front perspective view of our design; FIG. 3 is a top plan view of our design; FIG. 4 is a bottom plan view of our design; FIG. 5 is a front elevation view; FIG. 6 is a rear elevation view; FIG. 7 is a right side elevation view; FIG. 8 is a left side elevation view; FIG. 9 is a view of our design with the foot-straps removed; and,

FIG. 10 is a view of a second version of our design showing a plain unadorned top surface, the pattern is shown in dotted relief.

The broken lines depict portions of the foot-straps that form no part of the claimed design.
